Geo. D. Phillips, ATTORNEY

UNITED STATES PATENT OFFICE.

THOMAS F. COONEY, OF NEW HAVEN, CONNECTICUT.

FRUIT-CORING DEVICE

Application filed April 16, 1926. Serial No. 103,426.

This invention relates to a new and improved coring device of the type used for coring and seeding grape-fruit and other fruit.

5 In connection with a tubular cutter for enclosing the core, the object of the present invention is to provide means whereby the core is forced against the inner wall of the tubular cutter to squeeze the juice therefrom and deposit the exhausted core outside of the 10 tubular cutter.

Referring to the accompanying drawings wherein the same numerals of reference indicate like parts throughout the several 15 views—

Figure 1 represents a front elevation of the device—

Figure 2 is a elevation looking in the direction of arrow *a*, Figure 1—

20 Figure 3 is a sectional view of the tubular cutter showing the normal position of the combined core extractor and core compressor, also broken view of one of the arms of the handle—

25 Figure 4 is a similar view of the tubular cutter and handle showing the extractor forced against the opposite inner wall of the tubular cutter—

Figure 5 is an end view of the device looking in the direction of arrow *b*, Figure 1—

30 Figure 6 is a detail view of the extractor and its supporting rod, and

Figure 7 is a detail view of the core extractor and core compressor.

35 The tubular cutter 1 has its lower end beveled to form the cutting edge 2. The handle is formed of a single piece of metal comprising the head portion 3 and the spaced sides or arms 4, 5, embracing the cutter and are secured thereto by the rod 6 passing through the cutter 1. Each arm has an elongated slot therethrough similar to the slot 7 in the arm 4, Figures 2, 3, and 4, for the free admission of the rod 8 on which are mounted the outer 40 finger supports 9. The scoop shaped core extractor and compressor 10 has the bottom 11 and housing 12 by means of which it is journaled on the rod 6. The extractor actuating lever 13 is pivotally supported to the 45 rod 8 of the handle and the pin 14 of the standard 15 of the extractor.

In operating the device, the lever 13 is first actuated by forcing the finger supports 9 downward to carry the extractor 10 over against the inner wall of the tubular cutter 55 as shown in Figure 3. The cutter 1 is then forced down into the center of a halved fruit to envelop and enclose the core, when an upward pull against the finger supports 9 will carry the extractor over from its normal position, Figure 3, to the opposite inner wall of the cutter, Figure 4, detaching and carrying the core with it.

During the withdrawal of the cutter 1 from the fruit, the upward pull on the knobs 65 9 will continue to be exerted and thus thoroughly squeeze the core and discharge the juice therefrom back into the fruit. The pressure on the supports 9 is then reversed to carry the extractor to its normal position 70 when the exhausted core will readily fall out of the tubular cutter.

Various minor changes in the general construction of the combined core extractor and core compressor could be effected without interfering with its main and principal function of detaching and compressing the core. If desired, the perforations 16, Figure 7, could be formed in the side of the extractor, and also in bottom 11 as well, to facilitate 75 80 the discharge of the juice. Minor changes could also be made in the mechanism for actuating the extractor without departing from the spirit of my invention.

Having thus described my invention what 85 I claim is—

1. A coring device of the character described, comprising a tubular cutter, a handle connected therewith, and a combined core extractor and core compressor within the 90 tubular cutter and operatively connected with the handle.

2. A coring device of the character described, comprising a tubular cutter, a handle connected therewith, a combined core 95 extractor and core compressor pivotally supported within the tubular cutter, means operatively connected with the extractor for oscillating the extractor within the tubular cutter.

3. A coring device of the character described, comprising a tubular cutter, a handle 100

connected therewith, a combined core extractor and core compressor operatively located within the tubular cutter, and means outside the tubular cutter for actuating the extractor to sever and compress a fruit core.

4. A coring device comprising a tubular cutter, a handle connected therewith, a combined core extractor and core compressor

pivottally supported within the tubular cutter, and movable finger supports operatively connected with the extractor to actuate said extractor to sever and compress a fruit core.

In testimony whereof I affix my signature.

THOMAS F. COONEY.
